CONTROL CONSOLE

Eliot Noyes, New Canaan, Conn., and Leon M. Cooper
and Edwin R. Wyma, Lexington, Ky., assignors to In-
ternational Business Machines Corporation, New York,
N.Y., a corporation of New York

Filed Apr. 21, 1964, Ser. No. 79,624

Term of patent 14 years

(Cl. D26—5)

FIG. 1

FIG. 2

FIG. 3

FIG. 4

FIG. 5

FIG. 6

FIG. 1 is a front perspective view of a control console, showing our new design;

FIG. 2 is a rear perspective view thereof;

FIG. 3 is a plan elevation thereof;

FIG. 4 is a left side elevation thereof;

FIG. 5 is a front elevation thereof;

FIG. 6 is a right side elevation thereof.

The dominant features of our design reside in those portions shown in full lines on the drawing.

We claim:

The ornamental design for a control console, substantially as shown and described.
